CAR GENERATOR DRIVE

Frank L. Morse, Ithaca, N. Y.

Application October 5, 1932, Serial No. 636,322

8 Claims. (Cl. 105—102)

This invention relates to means for transmitting mechanical power from an axle or drive shaft having a large amount of longitudinal motion, lateral motion, and angular displacement, to a relatively fixed driven shaft by means of a belt or gearing transmission system whose elements are held in strict alignment. It is particularly applicable to electric generators for railway cars, which are ordinarily driven by means of a belt from a pulley mounted on the axle of the car truck, while the generator is mounted on the underside of the car body. The ordinary belt drives have given trouble due to the fact that the axle takes up various positions relative to the car body when running and going around curves, so that the belts frequently jump the pulleys and are subject to excessive wear due to running out of line.

In the present invention, I mount the driving pulley on the axle by means of slightly flexible rods which permit extended movement of the pulley along the axle, thru the use of sliding or roller elements between the rods and the pulley. The driving pulley, being thus free to adjust itself relative to the axle, can be held in line with the driven pulley by any suitable means attached to the car body.

Referring now to the drawings forming part of this application:

30 Fig. 1 is a vertical elevation, partly in section, along the line of the axle, showing the manner of mounting the driving rods;

35 Fig. 2 is a transverse elevation and section thru the line 2—2 of Fig. 1, showing the means for clamping the rods to the axle;

40 Fig. 3 is a transverse elevation and section showing the driving pulley and the means for mounting it to the car frame, with details of the driving rollers on the rods;

45 Fig. 4 is a section along the line 4—4 of Fig. 3 showing the means for guiding the drive pulley and for maintaining it against lateral displacement;

50 Fig. 5 is a general view in side elevation, partly in section, showing the invention as applied to drive an electric generator from the axle of a railway car;

55 Fig. 6 is an end elevation of a modified form in which the rods pass thru sliding friction bearings provided with a lubricating system;

Fig. 7 is a transverse elevation and section of a split pulley of the pressed metal type preferably used with the form shown in Fig. 6;

55 Fig. 8 is a detail showing another form of oil

seal which may be used with the modification shown in Figs. 6 and 7;

Fig. 9 is an elevation of one of the bushing housings and oil seals, as indicated by the line 9—9 of Fig. 6;

Fig. 10 is a cross-section on the line 10—10 of Fig. 6 showing the lateral bearing shoes which maintain the drive pulley in alignment with the car body and the driven pulley;

Fig. 11 is a cross-section along the line of the axle, showing a V-belt drive pulley, with friction bushings for the drive rods;

Fig. 12 is an end elevation and section on the line 12—12 of Fig. 11;

Fig. 13 is a cross-section thru the V-pulley rim on the line 13—13 of Fig. 12;

Fig. 14 is a detail cross-section on a larger scale of the sliding bushing and rod lubricating system; and

Fig. 15 is a lateral elevation of one form of clamping means by which the rods are clamped to the axle.

Similar reference numerals refer to similar parts throughout the various views.

In the ordinary railway car design using six wheel trucks, the electric generator which is used for lighting, refrigeration, etc., is driven by a belt from a pulley on the third or rear axle of the truck.

When the car rounds a curve this third or rear axle swings to the right or left and tends to throw the belt out of alignment. One of the objects of the present invention is to overcome this difficulty, and referring now to Fig. 1 and Fig. 2, there is shown the car axle 1 on which are clamped the flanges 2 mounted on the spacing tube 3.

The flanges 2 carry rubber bushings 2' supporting the driving rods 4, which are sufficiently long to allow for the transverse swing of the truck, and sufficiently flexible to yield slightly under any binding or twisting strains.

The driving rods 4 are however sufficiently strong and rigid to be adequate to transmit the full driving torque from the axle 1 to the driving pulley 6. The flanges 2, spacing tube 3 and driving rods 4, all being clamped to the axle 1, all rotate as a unit when the axle revolves.

If desired, the rods 4, while substantially straight, may be bent slightly outward on a curve to relieve any binding action when the pulley 6 assumes a diagonal position, especially when near the supporting flanges.

The driving pulley 6 is mounted in a movable frame 7 which is rigidly held against transverse motion relative to the car body so that the belt is always maintained in definite alignment with the driven pulley 8. The general arrangement is

110

shown in Fig. 5, and in greater detail in Figs. 3 and 4. In these figures, the main beams of the car body are indicated by the reference numerals 10. A pivot bearing 11 is attached to the car beams 10 and pivotally supports a link 12, which in turn carries in a fork 13 at its lower end the pulley guide frame 7. This guide frame 7 is pivotally mounted on the thru bolt 14, and consists of two parts bolted together by the bolts 15. The driving pulley 6 (see Figs. 1 and 4) is rotatably mounted between the two sides of the frame 7, and runs between suitable bushings 16 as shown in Fig. 4.

The transverse driving rods 4 are clamped to the axle and extend thru openings in the driving pulley 6, these openings being provided with grooved rollers 18 whose axes extend at right angles to the rods 4 and in the plane of the pulley 6. The rollers 18 are preferably provided with anti-friction bearings, and the driving rods 4 extend thru the grooves of the rollers 18. The grooves of the rollers 18 are sufficiently deep, that is, they have sufficiently high side flanges, so that the rods 4, as they rotate with the axle 1, will transmit the rotating driving force to the pulley 6, while at the same time the rollers 18 permit the rods 4 to slide freely longitudinally thru the pulley 6, as the truck shifts from side to side. The link 12 permits the frame 7 to adjust itself to the axle. The frame 7 is in general supported by the rods 4, but is held from side-ways motions by the link 12.

A V-belt 20 is shown running from the driving pulley 6 to the driven pulley 8 of the electric generator 21, which may be supported in the usual manner from the car beams 10.

Another and somewhat simpler form is shown in Figs. 6, 7, 8, 9 and 10. This uses a pressed steel split pulley 6', fixed guide shoes 12' in place of the linkage 12, and driving holes bushed with lubricated bearing material 18' to receive the drive rods 4.

Referring now more in detail to Figs. 6 to 10 inclusive, the driving pulley 6' is split for mounting, is bolted together by the bolts 25 as shown in Fig. 6, and the pulley face is provided with wide side flanges 26, which are utilized as bearing faces to take the end thrust. The driving pulley 6' is held in a definite transverse position or alignment with the car body by means of the fixed arms 27 which are bolted to the car beams 10 and carry thrust shoes 12' (as shown in Fig. 6 and Fig. 7, and in cross-section in Fig. 10), which bear against the sides of the pulley 6'. The driving pulley 6' is thus held in definite alignment with the driven pulley of the electric generator, but aside from this transverse guidance the driving pulley 6' is free to move around in the driving plane to adjust itself to any movement of the axle.

The pulley 6' is driven by the rods 4 which are clamped to the axle as previously described, an alternative form of clamping means 2' being illustrated in Fig. 15. The rods 4 pass through lubricated bushings 18' which are carried in oil tight housings 30. These housings 30 are provided with oil seals 31 of the usual construction, generally of felt or leather, and the bushings 18' are drilled at 31' for lubrication. The oil casings 32 or reservoirs 30 are connected by the tubing 32 so as to equalize the oil flow. The drive rods 4 play freely back and forth thru the bushings 18', rubbing on the lubricated surfaces as the truck swings in rounding a curve of the track.

75 A somewhat similar modification is shown in

Figs. 11, 12, 13, 14 and 15. This is for a V-belt, as in Figs. 1 to 4, but has the lubricated drive rod bushings as in Figs. 6 to 9 inclusive. Instead of external oil pipes 32, however, the pulley 6'' is provided with an annular internal oil hole 32' 80 which runs from one bushing to another, the oil passing around each bushing by means of an annular groove 35 in the seat (see Fig. 14).

With the coming of electrical refrigeration and air conditioning for railway cars, one of the problems is to increase the output of the generators. Without increasing the size of the generator, this added output can only be obtained by increasing the speed; that is, by increasing the diameter of the driving pulley. When the driving pulley is maintained in a definite transverse position as above described, it may be extended up between the beams of the car body, which is not possible where the belt has transverse play as in the ordinary generator drive. 90

95 While in the foregoing I have described certain specific examples, it will be understood that they are merely for the purpose of illustration to make clear the principles of the invention, which is not limited to the particular forms 100 shown, but is susceptible to various modifications and adaptations in different installations as will be apparent to those skilled in the art, without departing from the scope of the invention as stated in the following claims:

1. In a power transmission, the combination of an axle, a body mounted to have movement relative to said axle, a driven pulley mounted on said body, a frame mounted in definite alignment with said driven pulley, a driving pulley maintained in alignment with said driven pulley by said frame, said driving pulley being free to move in the driving plane with the movements of the axle, rods secured to said axle to rotate therewith and extending in driving relation thru the driving pulley and along the direction of the axle a sufficient distance to allow the axle to swing on a curve, said rods being sufficiently flexible to maintain a driving relation with the driving pulley when in a diagonal position as when 105 rounding a curve.

2. In a power transmission, the combination of an axle, a body mounted to have movement relative to said axle, a driven pulley mounted on said body, a frame mounted in definite alignment 115 with said driven pulley, a driving pulley maintained in alignment with said driven pulley by said frame, said driving pulley being free to move in the driving plane with the movements of the axle, rods secured to said axle to rotate therewith and extending in driving relation thru said driving pulley and along the direction of the axle a sufficient distance to allow the axle to swing on a curve, and radially fixed bearing means mounted in the driving pulley to receive the driving 130 force of the rods, said rods being sufficiently flexible to maintain a driving relation with the driving pulley when in a diagonal position as when 135 rounding a curve.

3. In a power transmission, the combination 140 of a body, a driven pulley carried by said body, an axle adapted to take up various angular and transverse positions relative to the body, flexible driving rods extending in the general direction of the axle and mounted to rotate therewith, a driving pulley supported by said rods and receiving driving torque therefrom while free to assume various positions longitudinally along said rods, and means carried by said body for main- 145 150

taining the driving pulley in alignment with the driven pulley.

4. In a power transmission, the combination of an axle, spaced clamping means secured to said axle, driving rods extending between said clamping means substantially parallel to said axle and secured at their ends to said clamping means so as to rotate with the axle, a driving pulley carried on said rods and receiving driving torque therefrom, said driving pulley being freely movable longitudinally relative to said rods, said rods being sufficiently flexible to maintain a driving relation with the driving pulley when in a diagonal position as when rounding a curve, and means for controlling the plane of rotation of the driving pulley.

5. In a power transmission, the combination of an axle, spaced clamping means secured to said axle, driving rods extending between said clamping means substantially parallel to the axle and secured at their ends to the clamping means so as to rotate with the axle, a driving pulley carried on said rods and receiving driving torque therefrom, said driving pulley being freely movable longitudinally relative to said rods, radially fixed bearing means mounted in the pulley to receive the driving thrust and longitudinal motion of the rods, said rods being sufficiently flexible to maintain a driving relation with the driving pulley when in a diagonal position as when rounding a curve, and means for controlling the plane of rotation of said driving pulley.

6. In a power transmission, the combination of an axle, spaced clamping means secured to said axle, driving rods extending between the clamping means substantially parallel to the axle and secured at their ends to the clamping means so as to rotate with the axle, a driving pulley carried on said rods and receiving driving torque therefrom, said driving pulley being freely movable longitudinally relative to said rods, radially fixed bearing means mounted in said pulley to receive the driving thrust and longitudinal motion of the rods, said rods being suffi-

ciently flexible to maintain a driving relation with the driving pulley when in a diagonal position as when rounding a curve, lubricating reservoirs connected to the bearing means and rotatable with the pulley, and means for controlling the plane of rotation of the driving pulley.

7. In a power transmission, the combination of an axle, spaced clamping means secured to said axle, driving rods extending between the clamping means substantially parallel to the axle and secured at their ends to the clamping means so as to rotate with the axle, a driving pulley carried on said rods and receiving driving torque therefrom, said driving pulley being freely movable longitudinally relative to the rods, radially fixed bearing means mounted in said pulley to receive the driving thrust and longitudinal motion of the rods, said rods being sufficiently flexible to maintain a driving relation with the driving pulley when in a diagonal position as when rounding a curve, said pulley having end thrust faces on its sides, and means engaging the end thrust faces for maintaining the plane of rotation of said pulley.

8. In a power transmission, the combination of an axle, spaced clamping means secured to said axle, driving rods extending between the clamping means substantially parallel to the axle and secured at their ends to the clamping means so as to rotate with the axle, a driving pulley carried on said rods and receiving driving torque therefrom, said driving pulley being freely movable longitudinally relative to said rods, radially fixed bearing means mounted in the pulley to receive the driving thrust and longitudinal motion of the rods, said rods being sufficiently flexible to maintain a driving relation with the driving pulley when in a diagonal position as when rounding a curve, lubricating reservoirs connected to the bearing means and rotatable with the pulley, said pulley having end thrust faces, and means engaging the end thrust faces for maintaining the plane of rotation of the pulley.
